UNITED STATES PATENT OFFICE

161,174

POWER MOWING MACHINE

Paul W. Hainke, Hutchinson, Kans., assignor to
The Paul Hainke Mower Corporation, Inc.,
Hutchinson, Kans., a corporation of Kansas

Application November 21, 1949, Serial No. 6,164

Term of patent 14 years

(Cl. D40—1)

To all whom it may concern:

Be it known that I, Paul W. Hainke, a citizen of the United States, residing at Hutchinson, in the county of Reno and State of Kansas, have invented a new, original, and ornamental Design for a Power Mowing Machine, of which the following is a specification, reference being had to the accompanying drawing forming a part thereof.

Fig. 1 is a perspective view of a power mowing machine, showing my new design;

Fig. 2 is a front elevational view thereof;

Fig. 3 is a rear elevational view thereof; and,

Fig. 4 is a fragmentary, bottom plan view thereof.

The dominant features of the design reside in the portions shown in full lines.

I claim:

The ornamental design for a power mowing machine, as shown and described.

PAUL W. HAINKE.
